UNITED STATES PATENT OFFICE.

HERBERT S. ATKINSON, OF EAST ORANGE, NEW JERSEY, ASSIGNOR TO THE HAYWARD COMPANY, OF NEW YORK, N. Y., A CORPORATION OF NEW YORK.

TOOTH-PLATE FOR EXCAVATING APPARATUS.

1,128,399.

Specification of Letters Patent. Patented Feb. 16, 1915.

Application filed July 5, 1912. Serial No. 707,885.

To all whom it may concern:

Be it known that I, HERBERT S. ATKINSON, a citizen of the United States, and resident of East Orange, in the county of Essex and 5 State of New Jersey, have invented certain new and useful Improvements in Tooth-Plates for Excavating Apparatus, of which the following is a full, clear, and exact specification, such as will enable others skilled 10 in the art to which it appertains to make and use the same.

This invention relates to teeth for excavating apparatus, such as buckets, dippers, and the like, and while the accompanying 15 drawings illustrate the invention as applied to the segments of a clam shell bucket, I desire it to be understood that it is not limited thereto, but may be applied to other analogous apparatus and uses.

20 I am well aware that it is not new in the art to provide with cutting teeth the biting lips or edges of dippers, buckets and other such apparatus, but heretofore it has been the custom to attach each individual tooth 25 separately to the digging implement, the result of which has been that if one of the teeth strikes a hard obstruction, to which blow the other teeth are not exposed, the uneven strain is apt to injure the lip or biting 30 edge of the bucket, and cause the same to buckle or become distorted.

The object of my invention is to provide 35 teeth for such apparatus which are formed preferably as integral parts of a bearing and stress member to be attached to the biting edge of a cutting member of a bucket, or the like, whereby the strains imposed 40 upon one or more of the teeth may be transmitted to and borne by the entire row of teeth, thereby avoiding the difficulties which have been present in the use of excavating teeth as heretofore provided. The bearing and stress member and its associated teeth I will herein term "tooth plates," and, so 45 far as I am aware, such tooth plates are new in the art.

A further object of my invention is economy in the cost of manufacture, and application, of such teeth to the digging implement.

The foregoing objects will be made clear by the following specification, taken in connection with the accompanying drawings, in which,—

55 Figure 1 is an elevation of the under side

of a bucket showing my improved tooth plates attached to the bucket segments; Fig. 2 is an enlarged elevation of the reverse side of one of the tooth plates shown in Fig. 1; and Fig. 3 is a side elevation of two teeth 60 of two opposing plates, with portions of the bucket segments shown in section.

Referring to the construction illustrated, A and B, respectively, represent the under sides of the usual and well known clam 65 shell bucket.

C, D, represent, respectively, the cutting shoes or blades of the bucket segments, each of which shoes carries a tooth plate, one of which is indicated, in whole, at E in Fig. 70 2, the edge of the cutting shoe being indicated in said figure at F. It will be understood that these tooth plates will be of any desired length to conform to the length of the cutting shoe or the width of the bucket 75 segments.

The tooth plates comprise a series of teeth F' formed as a part of and carried by a bearing and stress member G from the opposite side of which project rearwardly a 80 series of fastening arms H.

Formed upon the outer or wearing side of the tooth plates and transversely to the length of same are a series of reinforcing fins I, which, while acting to strengthen the 85 teeth F', and also serving as wearing surfaces therefor, are of such shape as to expose a relatively small cross sectional area to the material to be excavated. The fins I are provided with projections or bosses 90 J, through which project countersunk rivet holes K, and the rearward extensions or holding members H are provided with similar countersunk holes L, through the former of which, one set of rivets, as indicated at 95 M in Fig. 3, secure the tooth plates and cutting blades or shoes C, D, to the respective bucket segments A, B, and a separate set of rivets N, through the holes L, secure the holding members H to the respective bucket 100 segments. The exposed forward edge of the stress member G is beveled between the teeth F', as indicated in dotted lines at O, and the extreme outer edge of said member between said teeth is spaced from the biting 105 lip F of the cutting shoe, the arrangement being such that a considerable extent of the cutting edge of the shoes C, D, is left exposed to cut into the material, and the beveled edge O of the member G offers little 110

obstruction to the movement of the cutting blades through such material.

The inner surface of the tooth plates is formed with a shoulder indicated at P, 5 which affords an abutment for resting against the adjacent rearward edge of the cutting shoes C, D, and thereby aids in quickly and accurately positioning and fitting the tooth plates to the bucket segments.

10 What I claim is:

1. A tooth plate for attachment to the cutting-members of grab-bucket segments, comprising a holding and stress member, and digging teeth on and formed integral 15 with, said member, said teeth, at the points of juncture with said holding and stress member, being spaced apart, and said holding and stress member, between said teeth, being beveled at its forward side, the beveled edge thereof being so positioned as to normally lie spaced rearwardly from the cutting edge of the cutting member to which it is adapted to be applied.
2. In a bucket, the combination of the 25 bucket segments, a cutting member on each segment, a tooth plate on each of said cutting members, each tooth plate comprising a holding and stress member, and a plurality of digging teeth formed integral with 30 said last-named member and spaced apart thereon at the points of juncture with said

holding and stress member, to afford clearance spaces for the passage therebetween and overlapping said holding and stress member of the teeth of opposing plates, 35 said tooth plates being provided with position-finding shoulders adapted to bear against said cutting members, and means securing the respective bucket segments, cutting members and tooth plates together in 40 operative position.

3. In a bucket, the combination of the bucket segments, cutting members thereon, tooth plates on said cutting members, each comprising a holding and stress member 45 and a plurality of digging teeth formed integral therewith and spaced apart thereon at the points of juncture therewith to afford clearance spaces for the passage between said teeth and overlapping said holding and stress member of the teeth of opposing plates, said holding and stress member being beveled at its forward side between said teeth and spaced rearwardly from the cutting edge of the cutting member, and means 50 securing the respective bucket segments, cutting members and tooth plates together in operative position.

HERBERT S. ATKINSON.
